SURFACE GRINDING MACHINE

James Selby, Willesden, London, England, assignor to B. Elliott & Company Limited, London, England

Application January 8, 1952, Serial No. 265,369
In Great Britain December 1, 1950

(Cl. 51-55)

5 Claims.

1

The present invention relates to surface grinding machines, and concerns more particularly the means for advancing the grinding tool in relation to the surface of the work. The invention has for its object to provide for more efficient control of the advancement of the grinding tool, so as to permit of coarse or fine adjustment thereof at will.

The invention is applicable to any construction of surface grinding machine in which the grinding tool is advanced by rotation of a feed screw, adapted to be operated by manually operated means, either directly for coarse adjustment or through a reduction drive, at will for fine adjustment. Thus the feed screw may be positively associated with a hand wheel or other operating member, which is operable to give coarse adjustment, and may also be associated indirectly through a coupling device and a reduction drive with an operating member for fine adjustment, means being provided for disconnecting the reduction drive from the feed screw, when it is desired to operate the coarse adjustment.

It will be appreciated that the reduction drive must operate the feed screw through a coupling device, so that when coarse adjustment is desired the feed screw may be freed from the control imposed by the reduction drive, so that it is necessary to provide means for disconnecting the reduction drive from the feed screw to permit coarse adjustment thereof.

According to the present invention, therefore, the reduction drive comprises a worm element adapted to be rotated by the fine adjustment member, and a single helical toothed gear wheel combined with a coupling disc to form an axially movable combined member, which may be moved to engage with or disengage from a complementary coupling member carried by a member mounted on the feed screw.

According to further features of the invention, the axially movable combined member has a part thereof engaged with a slot in a rotatable member adapted to be rotated by a control member, so that rotation of said rotatable member causes axial movement of said combined member, to cause engagement or disengagement of the coupling means. The worm element is rotatable within the longitudinally slotted sleeve, which constitutes the rotatable member by means of which axial movement of the coupling member is controlled.

In the construction of the machine hereinafter described the worm element is mounted on an operating shaft, and is rotatable within an encircling sleeve, fitted into a bore in the machine adjacent and at right angles to the feed screw bore, said worm engaging through a slot in said sleeve with a helical toothed gear wheel coaxial with the feed screw, with which it may be drivingly coupled.

In order that the invention may be clearly understood and readily carried into practice, a surface grinding machine embodying the invention is illustrated, by way of example only, in the accompanying drawings, in which:

Figure 1 is a view of the machine in vertical section.

Figure 2 is a front elevation of the machine.

Figure 3 is a sectional view in section to a larger scale, of the fine adjustment mechanism and its control means, and

Figures 4, 5 and 6 are detail views, also to a larger scale, of the controlling sleeve.

Referring to the drawings, the machine comprises a base casting 1 on which is bolted a pedestal or standard 2, the upper end of which carries a radially extending rotatable head 3. Vertically slidable on the pedestal 2 is an arm 4 to which is bolted a casing 5 containing an electric driving motor 6, the shaft 7 of which carries at its lower end the grinding member 8, which is of cylindrical box or cup-like form. The motor casing 5 carries a pair of spaced radial arms 9 between which is mounted a bar 10 to serve as a hand-grip, whereby the arm 4 carrying casing 5 may be rotated angularly about the pedestal 2 during the grinding operation, or whenever required.

To protect the surface of the lower part of the pedestal 2, a flexible sleeve 22 of leather, or the like, enclosing the said lower part, is fastened between the base 1 and the lower part of the arm 4, this sleeve being long enough, when extended, to allow travel of the arm 4 to the upper end of pedestal or standard 2 and collapsing in concertina fashion as the arm 4 moves downwardly.

The vertical travel of the arm 4 on standard 2 is controlled by the feed screw 11, which is journalled in the head 3 and passes through a screw thread, and bore in arm 4, between the standard 2 and casing 5. The upper end of feed screw 11 carries a hand wheel 12 positively keyed thereto, by which the screw 11 may be rotated rapidly to give coarse adjustment of the position of the arm 4 along standard 2, and thus of the edge of grinding member 8 in relation to the surface of the work mounted on table 13 on base 1. The feed screw 11 may also be adjusted slowly and accurately to give a measured adjustment of grinding member 8 in relation to the work by a knob 14 from the side of head 3, close to feed screw 11, which is positively mounted on a short shaft 15 (Fig. 3), carrying a worm 16 which is housed in a sleeve 26, which has a longitudinal slot 27 to permit engagement of the worm 16 with a single helical toothed gear 17 slidable along the upper shank portion of feed screw 11, just below the hand wheel 12. The hub of the gear wheel 17 is extended upwardly, and has formed integrally therewith, a coupling disc 18 having a ring of

holes 19, at the same radius as a coupling pin 20 extending downwardly from the hub portion of hand wheel 12. Thus the combined gear wheel 17, and coupling disc 18, can be raised so that pin 20 engages in one of the holes 19 and thus a continuous driving connection is effected between the knob 14 (through worm 16 and gear wheel 17, coupling pin 20, hand wheel 12) and feed screw 11. Under these conditions, therefore, the feed screw 11 can be given small adjustments which can be regulated uniformly with the aid of graduations on the hub piece of knob 14, and a zero mark 24 on the end portion of sleeve 26 projecting from head 3. If however, the combined gear wheel 17 and coupling disc 18 are moved downwardly, so that pin 20 is disengaged from the coupling disc 18, the feed screw 11 will be released from the control of the worm drive, and freed for free rotation by hand wheel 12.

The slotted sleeve 26 serves as the means for moving the worm wheel 16 up or down, as may be required, to bring coupling disc 18 into or out of engagement with driving pin 20. The said sleeve 26 is rotatable in arm 4 and its end portion outside head 3 carries a radial operating lever 21, adjacent to knob 14, which may be used to rotate the sleeve 26, and this, by reason of the engagement of its slot 27 with the helical toothed gear wheel 11, raises or lowers the coupling disc 18, into or out of engagement with coupling pin 20. The sleeve 26 is held in position longitudinally by a retaining pin 28 engaged with a circumferential groove 29 in sleeve 26.

From the foregoing description it will be appreciated that the down feed of the grinding member is applied manually, either (a) by the hand wheel 12, which is primarily intended for coarse setting or (b) by the knob 14, by adjustment of which a cut may be applied by predetermined small increments.

The important feature of the foregoing construction is the slotted sleeve 26, which in itself provides the following features:

- (1) Permits of a plain straight bore for the worm shaft location.
- (2) Provides axial location for the worm and two journal bearings in a turned part without necessitating boring of the castings.
- (3) Provides simple means for disconnecting the worm drive from the feed screw 11 and releasing it for coarse adjustment by handwheel 12.

What I claim is:

1. A surface grinding machine comprising in combination a grinding tool, means for moving said tool towards the work, said means including a feed screw, a manually operable member on said feed screw for rotating said screw, and a fine adjustment means for rotating said feed screw to effect fine adjustments of said tool relative to the work, said latter means including a manually operated rotatable fine adjustment member, a reduction drive, a coupling device, and a control member, said reduction drive including a worm element rotatable by said fine adjustment member and a single helically toothed gear meshing with said worm element, said coupling device including a coupling disc fixed with said gear to form an axially slid able combined member and a cooperating complementary coupling member fixed with said feed screw, and said control member including a slotted member rotatable co-axially of said worm element with the slot defining edges of said member engageable with said axially movable combined member, and means for rotating said slotted member to cause axial movement of said combined member to en-

gage it with or disengage it from the complementary coupling member.

2. A surface grinding machine comprising in combination a grinding tool, means for moving said tool towards the work, said means including a feed screw, a manually operable member on said feed screw for rotating said screw, and a fine adjustment means for rotating said feed screw to effect fine adjustments of said tool relative to the work, said latter means including a manually operated rotatable fine adjustment member, a reduction drive, a coupling device, and a control member, said reduction drive including a worm rotatable by said fine adjustment member and a single helically toothed gear meshing with said worm, said coupling device including a coupling disc fixed with said gear to form an axially slid able combined member and a cooperating complementary coupling member fixed with said feed screw, and said control member including a sleeve surrounding and rotatable co-axially of said worm element, said sleeve being longitudinally slotted for engagement with said axially movable combined member and to allow engagement of the helically toothed gear with the worm, and means for rotating said slotted sleeve to cause axial movement of said combined member to engage it with or disengage it from the complementary coupling member.

3. A machine according to claim 2 wherein said sleeve is fitted in a bore in the machine frame adjacent to and at right angles to the feed screw, said helically toothed gear being engaged with the worm element through the slot in the sleeve.

4. A machine according to claim 3 wherein said worm is mounted on a shaft, an operating member for rotating said worm shaft, said coupling disc having a recess, and said complementary coupling member having a coupling pin engageable in said coupling disc recess upon axial movement of said disc.

5. A surface grinding machine according to claim 2 comprising a base plate, a vertical standard on said base plate, a radial arm slid able and rotatable on said standard, a casing carried by said arm, an electric motor within said casing and disposed with its spindle parallel to said standard and rotatably carrying said grinding tool at the lower end of said casing, and the feed screw being mounted parallel to the standard in a head rotatable on the upper end of said standard with said radial arm and casing, and passing through a female screw member in the part of said radial arm between said casing and said standard.

JAMES SELBY.
